YARN AND TAIL GUIDE FOR WINDING MACHINES

Royal Little, Providence, R. I., and Pacific J. Thomas, Scranton, Pa., assignors, by direct and mesne assignments, to U. S. Textile Machine Company, Scranton, Pa., a corporation of Pennsylvania

Application October 7, 1940, Serial No. 360,059

7 Claims. (Cl. 242—157)

This invention relates to a type of yarn winding machine which is commonly known as an "up-twister." In such machines the yarn is drawn upward from a yarn spool or other package on a constantly rotated twister spindle and is wound in a yarn package on a sleeve or tube, said latter package being driven at a constant surface speed.

It is desirable in many instances that the first few turns of yarn on the yarn sleeve or tube be so wound that they may be easily pulled out from the completed package to form a "tail" which may be tied to the outer end of yarn on an adjacent package, when the yarn is being prepared for use in a subsequent operation.

It is the general object of our invention to provide an improved yarn and tail guide for up-twisters and similar machines, which guide is adapted to guide the yarn in winding a "tail" at either end of a yarn package, and also to guide the yarn during the usual winding operation.

Our invention further relates to arrangements and combinations of parts which will be herein-after described and more particularly pointed out in the appended claims.

Preferred forms of our invention, as embodied in a winding machine of the up-twister type, are shown in the drawings, in which

Fig. 1 is a partial front elevation of a portion of such a winding machine;

Fig. 2 is a sectional side elevation of the mechanism shown in Fig. 1;

Fig. 3 is an enlarged front elevation of one form of our improved yarn and tail guide and certain associated parts;

Fig. 4 is a partial plan view, looking in the direction of the arrow 4 in Fig. 3;

Fig. 5 is a partial longitudinal sectional view, taken along the line 5—5 in Fig. 3;

Figs. 6 and 7 are transverse sectional views, taken along the line 6—6 and 7—7 in Fig. 3 respectively;

Fig. 8 is a side elevation of a modified construction of yarn and tail guide; and

Figs. 9, 10 and 11 are transverse sectional views, taken along the lines 9—9, 10—10, and 11—11 respectively in Fig. 8.

Referring particularly to Figs. 1 and 2, we have shown parts of a winding machine of the "up-twist" type, comprising a twister spindle 10 on which a supply spool S or other yarn package is mounted for rotation at constant speed. The yarn Y is drawn upward from the spool S through a guide-eye 12, then over our improved yarn and tail guide G, and through a traverse guide 15

pivotedly mounted on a reciprocated traverse rod 16.

The yarn Y is wound on a sleeve or tube T which is frictionally held on a roll 20, which in turn is pivotally mounted in the forked upper ends of a swinging supporting frame 22. The roll 20 and the yarn thereon is yieldingly pressed against a driving drum 25 by a spring 26, and the drum 25 is constantly rotated by a driving shaft 27.

The tube T is preferably provided with a shallow groove 30 in its outer surface and near one end of the tube, and the roll 20 is preferably provided with a V-shaped annular groove 32.

Our invention relates particularly to the construction of the yarn and tail guide G shown in one form in Figs. 3 to 7. The guide G comprises a substantially cylindrical body portion 40 having slightly enlarged end portions 41 and 42, which in turn are provided with hooks 43 and 44, all preferably formed integral in a single porcelain casting. The hooks 43 and 44 are spaced apart somewhat further than the length of the regular yarn traverse.

The guide G has a hole 45 extending axially therethrough which loosely receives a supporting rod 50. The rod 50 is secured by screws 51 in fixed frame members 52, which members also support upper and lower guide-rolls 53 and 54 for the traverse bar 16.

The end portion 42 of the guide G is provided with an enlarged recess 55 (Fig. 5) and with a transverse opening 56. A collar 60 is loosely seated in the recess 55 and is secured in position on the rod 50 by a set screw 62 which extends out through the opening 56. The collar 60 and screw 62 thus constitute means for holding the guide G on the rod 50 in any selected axial or angular position. The guide can be readily adjusted either axially or angularly by simply loosening the screw 62.

In Fig. 1 I have indicated the path of the yarn Y and the operation of the guide G when winding the initial turns or "tail" on the tube T. When starting the winding operation, several turns of the loose end of the yarn Y are crowded into the V-shaped notch 32 in the roll 20 to secure the yarn end, and the yarn is then placed under the hook or horn 43 on the guide G. As the yarn is drawn upward from the twister spindle by rotation of the roll 20, the hook 43 guides the yarn to the groove 30 which is near the end of the tube T and beyond the usual yarn traverse. After a desired number of turns have been wound in the groove 30, the yarn is then manual-

ly released from the hook 43 and is threaded in the yarn guide 15 which thereafter traverses the yarn on the tube T in the usual manner to form a desired yarn package.

If the direction of rotation of the twister spindle 10 is reversed, the roll 20 and its tube T will be reversed end-for-end in the supporting frame to bring the groove 30 to the left, and the tail will be wound with the yarn guided by the hook 44 instead of by the hook 43 as shown in the drawings.

We have thus provided a single-piece porcelain guide which is well adapted to guide the yarn during the usual winding operation and which is also adapted to guide the yarn when winding a tail on the tube, whether the spindle has a clockwise or an anti-clockwise direction of rotation. We have also provided extremely simple means for adjusting the guide both axially and angularly on its supporting rod 50.

In Figs. 8 to 11 we have shown a modified construction in which a porcelain yarn guide 70 is mounted on a rod 71 and is provided with hooks 72 and 73, all as previously described. The guide 70 is, however, formed of U-shaped transverse section, as clearly shown in Fig. 10, and with a longitudinal slot 75 running lengthwise thereof and adapted to freely receive the rod 71.

The guide 70 is provided with an end recess 76 to receive a collar 77, and is also provided with a transverse or radial opening 78 to loosely receive a binding screw 79 which engages the rod 71 and also projects outward into the opening 78. The collar 77 corresponds to the collar 80 (Fig. 5) previously described, and loosely positions the guide 70 both longitudinally and angularly on the rod 71.

At its opposite end, the guide 70 is provided with a recess 80 to receive a collar 81 having a slot 82 in one side thereof and having a binding screw 83 engaging the rod 71.

This modified construction is of considerable advantage when successive winding machines are mounted so closely together that endwise removal of the rod 71 is difficult or impossible. With this construction, a yarn guide 70 may be removed by loosening the screw in the collar 77 and sliding the collar 77 to the left in Fig. 8 far enough so that the guide 70 may be freed from both collars, after which it may be removed radially from the rod 71. Endwise removal or displacement of the rod 71 is thus unnecessary.

This modified construction possesses all of the uses and advantages previously described with reference to the construction shown in Figs. 3 to 7.

Having thus described our invention and the advantages thereof, we do not wish to be limited to the details herein disclosed, otherwise than as set forth in the claims, but what we claim is:

1. In a winding machine, a fixed supporting rod, a one-piece yarn and tail guide loosely

mounted on and entirely supported by said rod, said guide having a portion with an axially elongated and substantially cylindrical yarn-guiding surface and having an integral tail-winding hook

5 at each end of said body portion, and said guide being axially and angularly adjustable on said rod, and a single device effective to locate and secure said guide in both axially and angularly adjusted position on said rod.

10 2. In a winding machine, a supporting rod, a one-piece yarn and tail guide having a longitudinal passage therethrough to loosely receive said supporting rod and having an enlarged recess at one end of said passage and a communicating

15 radial opening, a collar on said rod loosely fitting said recess, and a set-screw in said collar extending out through said radial opening and thereby positioning said yarn and tail guide both longitudinally and angularly on said rod.

20 3. A yarn and tail guide for a winding machine comprising a tube having an elongated smooth body portion to guide the yarn during the regular winding of a yarn package and having a hook at one end of said tube adapted to guide the yarn

25 in winding a tail at one end of said yarn package, a positioning collar, said tube being recessed at one end to receive said collar and having a radial opening communicating with said recess and co-acting with a set-screw in said collar to axially and angularly position said collar and tube on a supporting structure.

30 4. In a winding machine, a supporting rod, a one-piece combination yarn and tail guide mounted on said rod and longitudinally slotted to freely receive said rod, means to position one end of said guide angularly and longitudinally on said rod and to prevent transverse displacement thereof, and means to prevent transverse displacement of the other end of said guide with respect to said rod.

35 5. In a winding machine, a supporting rod, a one-piece combination yarn and tail guide mounted on said rod and longitudinally slotted to freely receive said rod, said guide having a guide hook near one end and having enlarged axial recesses at both ends, collars on said rod loosely fitting said recesses and thereby preventing transverse displacement of said guide relative to said rod, and means to secure said collars in adjusted positions on said rod.

40 6. The combination in a winding machine as set forth in claim 5, in which one of said collars is longitudinally slotted to receive said rod.

45 7. The combination in a winding machine as set forth in claim 5, in which said guide has a transverse opening into one of said recesses and in which the associated collar has a clamping screw extending out into said transverse opening and loosely fitting said opening and thereby 50 positioning said guide both longitudinally and angularly with respect to said rod.

ROYAL LITTLE.
PACIFIC J. THOMAS.
